UNITED STATES PATENT OFFICE

EDWARD A. SUVERKROP, OF SEA CLIFF, NEW YORK.

LAPPING-MACHINE.

1,257,046.

Specification of Letters Patent. Patented Feb. 19, 1918.

Application filed March 23, 1917, Serial No. 156,853. Renewed January 2, 1918. Serial No. 210,072.

To all whom it may concern:

Be it known that I, EDWARD A. SUVERKROP, a citizen of the United States, residing at Sea Cliff, Long Island, in the State of New York, have invented a new and useful Improvement in Lapping-Machines, of which the following is a specification.

This invention relates to the making of gage blocks and the like metal pieces which are required to be very accurate as to thickness, and as to the parallelism, flatness and smoothness of their opposite surfaces.

The object of the present invention is to provide mechanism which will lap hard metal in such manner that gage blocks as satisfactory as standard hand made gages can be produced, having extremely accurate dimensions and parallel, flat and smooth opposite surfaces, in a short time with a minimum amount of labor and by relatively unskilled persons.

Broadly, apparatus for attaining this end has two flat lapping plates either made of or charged with abrasive material, and one or both being movable toward and from the other, with means for setting these lapping plates absolutely parallel and maintaining them parallel, means for setting the lapping plates a positive distance apart and insuring their stopping when approaching at an exact distance from each other, a work plate for holding the pieces to be lapped between the lapping plates, and mechanism for imparting relative compound movement or movement in more than one direction between the work plate and the lapping plates, and desirably at different speeds, in order that every portion of the surfaces to be lapped shall be subjected to the action of the entire lapping surfaces, and thus eliminate materially the wear of the laps, and neutralize any heating and peening effect and insure uniform abrasion of the pieces lapped so that the product will be extremely accurate in dimensions, parallelism, flatness and smoothness and yet be relatively cheap.

Of the accompanying drawings Figure 1 shows a plan of a machine that embodies the invention, in which the lap plates are annular and stationary while the work holding plate is circular and is rotated rapidly on an axis that is revolved slowly so that the lapped pieces will travel in an hypocycloidal path between the lapping surfaces of the lap plates. Fig. 2 shows a side elevation of this machine. Fig. 3 shows a plan with

the upper lap plate removed. Fig. 4 shows a central vertical section of the machine. Fig. 5 shows a section of portions of two annular plates that may be used on the machine for preliminary lapping and grinding and bringing the pieces to be lapped to approximate size.

The machine illustrated has a cylindrical casing 1 mounted on a stationary bed 2. Resting on a flange 3 near the upper end of the casing is the annular lower lap plate 4. The upper surface 5 of this lap plate may be formed of or charged in the usual way with abrasive material. At three points about the sides of the lower lap plate are hubs 6 with vertical bores. In these bores and extending upwardly from the hubs are guide posts 7 that may be secured with their upper ends at any desired height by clamps 8.

The annular upper lap plate 9, which has its lower surface 10 formed of or charged with abrasive material, has hubs 11 with vertical bores that have a sliding fit on the guide posts which are clamped in the hubs of the lower lap plate. Sleeves 12 are shown as screwed onto the upper ends of the hubs 11, and turning in the top ends of these sleeves toward and from the upper ends of the guide posts are micrometer stop screws 13. Openings 14 are made transversely through the sleeves so that the upper ends of the guide posts and the lower ends of the stop screws may be observed and standard gage blocks 15 placed between these parts.

In the tapering bore of the casing a rotatable conical sleeve 16 is fitted. This sleeve may be rotated in the casing by any suitable means as, for instance, it may have on its lower end a spiral gear or worm wheel 17 engaged by a spiral pinion or worm 18 on a shaft 19 that may be driven by any convenient means so as to rotate the conical sleeve slowly. Extending through the rotatable sleeve and having its axis eccentric with relation to the axis of the sleeve is a shaft 20. Anti-friction bearings 21 may be provided for supporting this shaft in the sleeve. On the lower end of the eccentric shaft is a pulley 22 which may be driven by any convenient means so as to rotate the shaft rapidly. Fixed on the shaft at the upper end of the sleeve is a collar 23 and fastened to this by any suitable means, as screws 24, is the work holding plate 25. Washers 26 are located on the shaft between

the collar and work plate so as to locate the work plate in proper position for efficient service between the lower and upper lap plates. The work plate in this type of machine is circular and is provided with a number of recesses arranged annularly near its periphery, and in these recesses are placed the pieces or blocks 27 to be lapped.

- In using the machine illustrated before 10 the work plate is placed in position the upper lap plate is placed on the guide posts with its lapping surface resting flatly on the lapping surface of the lower lap plate. With the lap plates together in this manner 15 the stop screws are turned down until they impinge on the upper ends of the guide posts. The upper lap plate is then lifted off and the work plate secured in position on the shaft with the pieces to be lapped in 20 the openings provided therefor, after which the upper lap plate is again put in place on the guide posts and standard gage blocks of the thickness to which the blocks carried by the work plate are to be reduced by lapping 25 are placed between the upper ends of the guide posts and the lower ends of the stop screws. As the blocks to be lapped are, of course, over size the lower ends of the stop screws are a slight distance above the tops 30 of the standard gage blocks on the upper ends of the guide posts. After the machine has been set in operation the work plate is rotated rapidly by means of the pulley and shaft and at the same time the sleeve is 35 rotated slowly by means of the spiral gears. This carries the axis of the rapidly rotating shaft slowly around in a circle, the radius of which is equal to the distance between the axis of the sleeve and the axis of the solid 40 shaft. As a result of these motions the work plate is, while rapidly rotated, slowly revolved so that the pieces being lapped, while carried rapidly around between the lapping surfaces of the two lap plates, are slowly 45 carried in and out between the inner and outer edges of the lapping surfaces of the lap plates. By means of this all the surfaces lapped are subjected to every portion of the lapping surfaces. The lapping is 50 continued until as the pieces are worn away the lower ends of the micrometer screws reach and impinge upon the upper surfaces of the standard gages on the guide posts, then, of course, as the upper plate can 55 scend no farther the lapping of the pieces ceases.

With this type of machine both the upper and lower lap plates, the lapping surfaces of which are made of or charged with hard 60 granular abrasive material, may be removed and the machine provided with lapping or grinding plates, such as shown in Fig. 5, for preliminary grinding. In this case the lower and upper plates 28 and 29 may be 65 grooved and rings of India oil stone 30 and

31 or other suitable grinding material may be cemented in the grooves of the rings. With the machine set up in this way the pieces to be formed into gage blocks, and which have previously been hardened and ground on a surface grinder to, say, within .001 of an inch of finished size, may be lapped so as to bring the pieces to approximately .0001 or .0002 of an inch over the finished size. The pieces having been reduced to this size are then lapped in the same machine provided with the lap plates first described or in another machine provided with such lap plates and reduced to finished size. In apparatus embodying this 80 invention pieces have been lapped very rapidly to less than .00005 of an inch of absolute dimension and parallelism.

With these machines a number of blocks may at the same time be by relatively unskilled labor quickly reduced to the dimensions of standard gage blocks without danger of the blocks curling, because both sides are heated and peened equally and simultaneously, and this insures that their 90 opposite surfaces be smooth, flat planes that are parallel.

The invention claimed is:

1. A lapping machine having parallel lap plates with abrasive opposing surfaces 95 mounted so the distance between them can be decreased, guides for insuring the parallelism of the lapping surfaces at all times, adjustable stops for limiting the closing together of the lapping surfaces, a work plate between the lap plates, and means for imparting relative movement between the lap plates and the work plate in more than one direction, whereby the opposite surfaces of the pieces carried by the work plate will 100 be subjected to the abrasive action of the lapping surfaces of the lap plates.

2. A lapping machine having parallel lap plates with flat abrasive opposing surfaces mounted so the distance between them can 110 be decreased, guides for insuring the parallelism of the lapping surfaces at all times, adjustable stops for limiting the closing together of the lapping surfaces, a work plate between the lap plates, and means for imparting relative movement between the lap plates and the work plate in more than one direction, whereby the opposite surfaces of the pieces carried by the work plate will 115 be subjected to the abrasive action of the lapping surfaces of the lap plates.

3. A lapping machine having parallel lap plates with flat abrasive opposing surfaces mounted so the distance between them can be decreased, guides for insuring the parallelism of the lapping surfaces at all times, 120 adjustable stops for limiting the closing together of the lapping surfaces, a work plate between the lap plates, and means for moving the work plate between the lap plates in 125

more than one direction, whereby the opposite surfaces of the pieces carried by the work plate will be subjected to the abrasive action of the lapping surfaces of the lap plates.

4. A lapping machine having parallel lap plates with flat abrasive opposing surfaces, one of which is movable toward the other, guides for insuring the parallelism of the lapping surfaces at all times, adjustable stops for limiting the closing of said movable lap plate toward the other lap plate, a work plate between the lap plates, and means for moving the work plate between the lap plates in more than one direction, whereby the opposite surfaces of the pieces carried by the work plate will be subjected to the abrasive action of the lapping surfaces of the lap plates.

5. A lapping machine having parallel lap plates with flat abrasive opposing surfaces mounted so the distance between them can be decreased, guides for insuring the parallelism of the lapping surfaces at all times, adjustable stops for limiting the closing together of the lapping surfaces, a work plate between the lap plates, and means for imparting relative rotary movement between the lap plates and the work plate in more than one direction, whereby the opposite surfaces of the pieces carried by the work plate will be subjected to the abrasive action of the lapping surfaces of the lap plates.

6. A lapping machine having parallel lap plates with flat abrasive opposing surfaces mounted so the distance between them can be decreased, guides for insuring the parallelism of the lapping surfaces at all times, adjustable stops for limiting the closing together of the lapping surfaces, a work plate between the lap plates, and means for rotating the work plate about its axis and revolving the axis of the work plate between the lap plates, whereby the opposite surfaces of the pieces carried by the work plate will be subjected to the abrasive action of the lapping surfaces of the lap plates.

7. A lapping machine having parallel lap plates with flat abrasive opposing surfaces, one of which is movable toward the other, guides for insuring the parallelism of the lapping surfaces at all times, adjustable stops for limiting the closing of said movable lap plate toward the other lap plate, a work plate between the lap plates, and

means for rotating the work plate about its axis and revolving the axis of the work plate between the lap plates, whereby the opposite surfaces of the pieces carried by the work plate will be subjected to the abrasive action of the lapping surfaces of the lap plates.

8. A lapping machine having parallel lap plates with flat abrasive opposing surfaces, one lap plate being stationary and the other movable toward the stationary plate, guides for the movable plate mounted on the stationary plate for insuring the parallelism of the lapping surfaces at all times, adjustable stops mounted on the movable plate for limiting the closing of said movable plate toward the stationary plate, a work plate between the lap plates, and means for rotating the work plate about its axis and revolving the axis of the work plate between the lap plates, whereby the opposite surfaces of the pieces carried by the work plate will be subjected to the abrasive action of the lapping surfaces of the lap plates.

9. A lapping machine having parallel removable annular lap plates with flat abrasive opposing surfaces mounted so the distance between them can be decreased, guides for insuring the parallelism of the lapping surfaces at all times, adjustable stops for limiting the closing together of the lapping surfaces, a work plate between the lap plates, and means for rotating the work plate about its axis and revolving the axis of the work plate between the lap plates, whereby the opposite surfaces of the pieces carried by the work plate will be subjected to the abrasive action of the lapping surfaces of the lap plates.

10. A lapping machine having parallel removable annular lap plates with flat abrasive opposing surfaces mounted so the distance between them can be decreased, guides for insuring the parallelism of the lapping surfaces at all times, adjustable stops for limiting the closing together of the lapping surfaces, a work plate between the lap plates, and means for rapidly rotating the work plate about its axis and slowly revolving the axis of the work plate between the lap plates, whereby the opposite surfaces of the pieces carried by the work plate will be subjected to the abrasive action of the lapping surfaces of the lap plates.
